UNITED STATES PATENT OFFICE.

AUGUST LAUBSCHER, OF SPRINGFIELD, MASSACHUSETTS, ASSIGNOR TO UNITED STATES ENVELOPE COMPANY, OF SPRINGFIELD, MASSACHUSETTS, A CORPORATION OF MAINE.

GUM-ROLL GOVERNOR FOR ENVELOP-MACHINES.

1,029,304.

Specification of Letters Patent. Patented June 11, 1912.

Application filed November 29, 1911. Serial No. 663,124.

To all whom it may concern:

Be it known that I, AUGUST LAUBSCHER, a citizen of the United States of America, residing at Springfield, in the county of 55
5 Hampden and State of Massachusetts, have invented a new and useful Gum-Roll Governor for Envelop-Machines, of which the following is a specification.

My invention relates to improvements in 10 gum-roll mechanisms for envelop-machines (such as the mechanism which forms the subject-matter of United States Letters Patent, No. 962,153, issued June 21st, 1910, and of which the present invention is in the 15 nature of an improvement) and more particularly to stop motions or devices for the gum-rolls of such mechanisms, and consists of certain peculiar mechanism for automatically interrupting the operation of the 20 gum-transferring roll when the envelop-blank support or elevator is lowered, so that the acts of receiving and transmitting gum by said roll are temporarily suspended, and for automatically starting the gum-roll 25 when said elevator is raised, all as herein-after set forth.

The object of my invention is to provide a simple but practical and efficient governor of few parts for the gum-roll-actuating 30 mechanism of an envelop-machine, which prevents the gum-roll from reciprocating while the elevator is lowered, and permits said gum-roll to resume operations upon the raising of said elevator, whereby an excessive 35 gumming of the gum-roll and pickers is avoided, likewise the spoiling of envelopes by the application thereto of too much gum.

As is well understood, the gum-roll transfers the adhesive material or gum from a 40 suitable source of supply at one end of the travel of said gum-roll to the pickers, and the latter in turn deposit the gum on the flaps of the envelop-blanks on the elevator. It is plain, therefore, that in the absence of 45 a governor for the gum-roll the latter will reciprocate constantly and so receive an excessive amount of gum and transfer to said pickers an excessive amount while the elevator is lowered for an additional supply 50 of blanks, there then being no blanks in position to receive the gum from the pickers as it is applied thereto. In consequence of

this the flaps of the first few blanks at the top of the replenished pile receive too much gum when such pile is raised into operative 55 position by the elevator, which necessitates the rejection of a like number of envelopes as defective. An extra and injurious amount of gum will be deposited on the flaps until the excessive amount on the roll or 60 on the roll and pickers, accumulated during the time required to lower the elevator, place a new pile of blanks thereon and raise the same, becomes exhausted, the objectionable transfer of surplus gum to 65 the blanks continuing until the quantity of gum on the transferring members diminishes sufficiently to restore such members to normal condition and bring about the transfer of gum to the flaps in the proper manner. 70

As before noted, my invention entirely obviates the difficulty and removes the objection just pointed out.

Other objects will appear in the course of 75 the following description.

I attain these objects by the mechanism illustrated in the accompanying drawings, in which—

Figure 1 is a front elevation of that part of an envelop-machine with which my invention is intimately associated and shows a practical form of said invention embodied therewith, the elevator being raised with a pile of envelop-blanks thereon and all members disposed in operative positions, excepting the governor latch-rod which is in its retracted and inactive position; Fig. 2, a detail in section of said latch-rod and the supporting bracket therefor at the outer terminal; Fig. 3, a perspective view of most of 80 the important members which are directly and indirectly involved in my invention, the elevator here being shown in its low position and the governor parts in their active positions with the gum-roll-actuating 85 mechanism, above the operating cam therefor, stationary; Fig. 4, a top plan of the operating lever or arm for the aforesaid latch-rod, and, Fig. 5, a front elevation of the lug or dog on the elevator by means of 90 which said arm is operated, and of said arm itself. 95

Similar figures refer to similar parts throughout the several views. 100

Generally speaking my invention comprises, with the gum-roll-actuating mechanism provided with a certain projecting member, a latch-rod adapted to be moved into and out of the path of travel of said member, and means for operating said latch-rod, such means being subject to the control of the elevator; the whole constituting governing mechanism or a governor for the gum-roll whenever said elevator is raised from or dropped to its low position, to the end that the action of the gum-roll is stopped each time said elevator is dropped and said gum-roll is set in motion each time said elevator is again raised, that is, such governor is automatically operated by the elevator and in turn throws out of action said gum-roll-actuating mechanism when the elevator is lowered or dropped and permits said mechanism to resume its normal action or function only when the elevator is raised, wherefore the gum-roll is inactive all the time that the elevator is down and is itself inactive.

Before describing my governor in detail and as illustrated in the drawings, I will first briefly mention the old parts of the envelop-machine therein appearing and which are more or less intimately associated with said governor, and so far as seems necessary or desirable explain the same.

Portions are shown of a table 1, an end standard 2, a front arch 3, and a rear arch 4. At 5 is one of a set of pickers attached to the base of a vertical rod 6 arranged to reciprocate through the arch 3. A front guide-rod 7, for a corresponding slide 8 of a gum-roll 9, is supported by horizontal arms 10-10 extending forward from the arch 4 and hangers 11-11 depending from the front ends of said arms. Suitably journaled below the table 1 is a rock-shaft 12 to which are rigidly attached two upwardly-extending actuating arms for the gum-roll 9, one such arm only being shown at 13, and a laterally-extending arm 14. Each arm 13 is connected with the corresponding gum-roll slide 8 by a rod 15. 16 is a cam- and spring-actuated arm for imparting motion to the rock-shaft 12 through the medium of a connecting-rod 17, such arm having its rear terminal pivoted at 18 to the standard 2. The arm 16 is provided with a roller 19 which normally rides on a cam 20 mounted on a suitably journaled shaft 21. A spring 22 is arranged to draw the arm 16 downward with the roller 19 on the cam 20. A gum-box 23, for the gum-roll 9, is upheld by a bracket 24 fastened to one leg of the arch 3. Fastened to the underside, of the table 1 is an elevator frame 25 in which an elevator 26 is arranged to move up and down. The elevator 26 is provided with a platform 27 for envelop-blanks 28.

When in operation the gum-roll 9 receives

its supply of gum from the gum-box 23 and deposits it on the bottom of the pickers 5 which in turn transfer it to the blanks 28 one after another, all in the usual and well-known manner.

A horizontal shaft 29 is journaled in suitable bearings on the elevator frame 25 and has two pinions 30 to mesh with the same number of racks 31 on the elevator 26. On the front terminal of the shaft 29 are a ratchet-wheel 32 and a hand-wheel 33. A detent 34, for the ratchet-wheel 32, is pivoted at 35 to the adjacent part of the frame 25, and a spring 36 normally draws said detent into engagement with said ratchet-wheel. On the front edge of the frame 25 is a lifter-bar 37 having a limited vertical movement and carrying an actuating pawl 38 normally pressed into engagement with the ratchet-wheel 32 by means of a spring 39 also on said lifter-bar. The lifter-bar is given an upward tendency by means of a spring 40. A rock-shaft 41, suitably mounted in front of the table 1 and above the plane thereof, carries two rearwardly-extending paper fingers 42. In addition to these members, means, such as those shown more fully and described in the hereinbefore-mentioned patent, are provided for depressing and elevating the lifter-bar 37 from the rock-shaft 41.

When the machine is in operation, the lifter-bar 37, acting through the intervening ratchet mechanism, raises the elevator 26 step by step for the purpose of presenting the blanks 28 at gumming position, said elevator traveling upward intermittently until the last blank is removed therefrom. The hand-wheel 33 is employed to raise the elevator with a pile of blanks thereon until the uppermost blank is in range of the pickers. The elevator is released and permitted to drop by pressing downward on the tail of the detent 34 and thereby throwing said detent and the pawl 38 out of engagement with the ratchet-wheel 32.

I will now take up the new features.

The connecting-rod 17 is provided with a suitable fixed member, in the form of an adjustable two-piece clamp collar 43 in the present case, which affords a shoulder so arranged on said connecting-rod that a horizontal latch-rod 44 can be thrust beneath it when the arm 16 is supported on the high part of the cam 20, said connecting-rod with said collar then being in the most elevated position. When the connecting-rod is in this position, the gum-roll 9 is at the right-hand end of its travel, or at the most distant point from the gum-box 23, being thus disposed by the rocker-arm 14, the rock-shaft 12, the rocker-arm 13, the rod 15, and the slide 8.

The two sections of the clamp collar 43 are fastened together on the connecting-rod 13.

17 by means of bolts and nuts in the usual manner, and this enables me to adjust said collar at the proper height on said connecting-rod to coöperate with the latch-rod 44 in supporting the parts as hereinafter explained. The upper edge of the collar 43 which is contiguous to the latch-rod is chamfered, as shown at 45.

5 The latch-rod 44 is mounted to slide in suitable bearings at or adjacent to the ends thereof, one such bearing being fastened to the back side of the elevator frame 25 and appearing at 46, in Fig. 3, and the other bearing being in the standard 2 and a bracket 15 47 fastened to said standard on the outside thereof. The aforesaid bearings are located at the proper height to enable the latch-rod to be thrust beneath the collar 43 when the latter properly adjusted is in its highest position. The outer end of the latch-rod is 20 beveled, as shown at 48, the inclination of such beveled part corresponding with that of the beveled or chamfered part 45 of the collar.

25 The latch-rod 44 is made in two sections so arranged as to afford an opportunity for the rod to yield when in the path of the collar 43 when it ascends. A slip joint is formed between the aforesaid latch-rod sections, which joint consists, as best shown in 30 Fig. 2, of a shank 49 at the inner end of one section and the adjacent terminal of the other section which has a longitudinal passage 50 therein to receive said shank, together with a spring 51 interposed between 35 adjacent ends of said shank and passage to thrust said first-mentioned section outwardly, and a pin 52 rising from said shank into a longitudinal slot 53 in the top wall of said passage to limit such outward movement and prevent rotation of either section 40 relative to its companion. The latch-rod as a whole is prevented from turning in its bearings by means of a pin 54 which extends 45 downwardly from the outer or nose-piece section into a central longitudinal slot 55 in the horizontal part of the bracket 47. The inward movement of the latch-rod is limited by the pin 54 in the slot 55, and a spring 50 50 56 is employed to retract said rod and retain it normally in a retracted position with said pin in contact with the inner end of said slot, such spring having one terminal attached at 57 to the section of the latch-rod 55 in which the passage 50 is located and the other terminal attached to the back of the elevator frame 25. Inserted in and projecting from the inner latch-rod section, between the point 57 and the bearing 46, are 60 two vertical pins 58 which are spaced apart.

Secured to the left-hand face of the frame 25, behind the rear rack 31, is a bracket 59, and pivotally mounted intermediate of its ends in this bracket, at 60, is an operating 65 lever or arm 61 for the latch-rod. The

back end of the arm 61 is forked at 62 to engage the latch-rod between the pins 58. The front terminal of the arm 61 extends to the right of a dog 63 which is securely fastened against the back side of the forward rack 31 and has a slanting edge 64, Fig. 5, to engage such terminal, the slant being from above downward to the left. The dog 63 is so positioned that, when the elevator 20 descends, said dog actuates the 75 front terminal of the arm 61 to the right and the rear terminal of said arm to the left and so causes the latch-rod 44 to be moved to the left against the resiliency of the spring 56. When the elevator ascends, 80 the dog 63 releases the arm 61 and the latch-rod to the spring 56, and the latter immediately draws said rod into its retracted position again.

Starting with the elevator 26 in its low 85 position, as shown in Fig. 3, the complete operation of the governor is as follows: The operator, after placing a pile of envelop-blanks 28 on the elevator platform 27, quickly rotates the hand-wheel 33, in the 90 direction of the arrow in said view, and thus raises said elevator until the top of said pile is brought into the field of operation of the fingers 42. The machine now commences to gum and remove the blanks 95 from the pile, one at a time, and the operator has nothing to do with the gumming and feeding of the blanks, but must drop the elevator again when the pile is exhausted or nearly so, as presently explained. 100

The aforesaid gumming operation commences, when the elevator is raised, because the slanting edge 64 of the dog 63 then releases the arm 61 and the latch-rod 44 to the action of the spring 56, and said spring at 105 once draws said latch-rod from beneath the collar 43, thus permitting the gum-roll-operating mechanism to follow the cam 20. The parts are now disposed as shown in the first view, and the gum-roll 9 is reciprocated 110 beneath the pickers in the usual manner.

The dog 63 and the arm 61 are so constructed, proportioned and arranged, and timed to the positioning of the elevator with its pile of blanks by means of the hand-wheel, that the blanks are in place ready to receive the gum by the time the gum-roll is brought into action, regardless of the size of the pile of blanks, provided a little care is exercised by the operator, and in any 115 event the raising of the pile into operative position need not be and, of course, should not be delayed long enough to allow the gum-roll to accumulate a sufficient amount of gum to spoil even one envelop. 120

The elevator continues to move upward under the influence of the lifter-bar 37 until the pile of blanks on the platform 27 has disappeared or it is desired to replenish the same, when the operator thrusts the detent 130

34 out of engagement with the ratchet-wheel 32 and thus permits said elevator to drop.

5 The dropping of the elevator instantly brings about a cessation of motion on the part of the gum-roll 9, and causes such roll to be left idle at the end of its path of travel which is opposite the gum-box 23, because the gum-roll is in that position when the 10 high part of the cam 20 is under the roller 19 and it is when the connecting-rod 17 with its collar 43 is thus elevated that the latch-rod 44 is thrust beneath said collar.

When the elevator 26 descends with the 15 dog 63, the latch-rod 44 is advanced through the medium of said dog and the arm 61, in the manner already explained, and if at this time the collar 43 happens to be in its highest position the beveled end of said 20 latch-rod at once slides under the adjacent side of said collar, but in the event said collar is below said beveled end of the latch-rod the collar in rising forces inward the outer section of said latch-rod, against the 25 resiliency of the spring 51, passes above the plane of said section, and then comes to rest on the contiguous end thereof, since said spring acts immediately to thrust said section into engaging position. In either 30 case the stopping of the gum-roll is brought about almost if not quite instantaneously, and it is stopped at the desired point.

Until the latch-rod is retracted by the 35 raising of the elevator again, the cam revolves without affecting the arm 16 and the parts connected therewith and actuated thereby.

From the foregoing it is plain that I have 40 greatly simplified the construction of the governor without impairing the usefulness of the same.

Modifications in the shape and size of the 45 governor members and minor changes in their construction and arrangement may be made without departing from the nature of my invention.

What I claim as my invention, and desire to secure by Letters Patent, is—

1. In an envelop-machine, the combination, with a gum-roll, and mechanism for operating the same, such mechanism being provided with a projecting member, of a member slidingly mounted adjacent to the path of travel of said projecting member, 50 an elevator, and a pivotally mounted member operated by said elevator in its downward movement to actuate said sliding member into said path to arrest the movement of said projecting member, said pivotally-mounted member being operatively connected with said sliding member.

2. In an envelop-machine, the combination, with a gum-roll, and mechanism for operating the same, such mechanism being 55 provided with a projecting member, of a

horizontal member slidingly mounted adjacent to the path of travel of said projecting member, a horizontal pivotally mounted operating member for such sliding member, and an elevator provided with means to actuate said operating member and thereby cause said sliding member to be thrust into said path to arrest the movement of said projecting member.

3. In an envelop-machine, the combination, with gum-roll-operating mechanism provided with a projecting member, of a horizontal member slidingly mounted adjacent to the path of travel of said projecting member and spring pressed in one direction, 70 a horizontal pivotally mounted operating member for such sliding member, and an elevator provided with means to actuate said operating member and thereby cause said sliding member to be thrust into said path to arrest the movement of said projecting member.

4. In an envelop-machine, the combination, with gum-roll-actuating mechanism provided with a projecting member, of a jointed longitudinally-yielding member slidingly mounted adjacent to the path of travel of said projecting member, a suitably mounted operating member for such sliding member, and an elevator provided with 90 means to actuate said operating member and thereby cause said sliding member to be thrust into said path to arrest the movement of said projecting member.

5. A gum-roll governor, for envelop-machines, comprising, with a gum-roll-actuating mechanism projecting member and an elevator projecting member, a slidingly-mounted latch-rod spring-pressed in one direction, such latch-rod being in operative 100 relation to said first-mentioned projecting member, and a pivotally-mounted arm connected with said latch-rod and being in operative relation to said second-mentioned 105 projecting member.

6. The combination, in an envelop-machine, of gum-roll-actuating mechanism consisting in part of a connecting-rod provided with a collar, a slidingly-mounted latch-rod spring-pressed in one direction and adapted to be thrust beneath said collar, a pivotally-mounted arm operatively connected with said latch-rod, and an elevator provided with a dog, said arm being in operative 110 relation to said dog.

7. The combination, in an envelop-machine, of gum-roll-actuating mechanism consisting in part of a connecting-rod provided with a collar, a slidingly-mounted latch-rod spring-pressed in one direction and adapted to be thrust beneath said collar, such latch-rod comprising two slidingly-arranged 115 spring-pressed sections, a pivotally-mounted arm operatively connected with said latch-rod, and an elevator provided with a dog,

said arm being in operative relation to said dog.

8. The combination, in an envelop-machine, of gum-roll-actuating mechanism consisting in part of a connecting-rod provided with a collar, a slidably-mounted latch-rod spring-pressed in one direction and adapted to be thrust beneath said collar, such rod having its outer end beveled, means

to prevent said latch-rod from turning on its axis, a pivotally-mounted arm operatively connected with said latch-rod, and an elevator provided with a dog, said arm being in operative relation to said dog.

AUGUST LAUBSCHER.
